UNITED STATES PATENT OFFICE.

IRVING C. BUCKMINSTER, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING ON PARTS OF BOOTS AND SHOES.

Application filed April 3, 1924. Serial No. 704,073.

This invention relates to machines for operating on parts of boots and shoes, for example, heels, heel lifts and heel bases, and particularly to positioning devices for locating a shoe part with respect to an operating tool, for example, a heel or heel part, with respect to a breasting knife.

For the purpose of exemplification the embodiment of the invention selected for illustration is shown as incorporated in a machine of the type disclosed in United States Letters Patents Nos. 1,475,794 and 1,475,795, granted November 27, 1923, on applications of Louis A. Casgrain. It is to be understood, however, that the invention is not limited in its application to machines of this type but that its novel features may be utilized in other machines for feeding and positioning shoe parts with respect to an operating means.

Features of the invention consist in an organization comprising an operating means and means for feeding a blank toward the operating means, with means engaging the blank and movable with the blank for aligning the blank with respect to the direction of feed of the blank or orienting it with respect to the plane of operation of the operating means. As shown herein, the lowermost heel in a heel magazine rests upon a feed table, and a feed slide engages the lowermost heel and moves it into position beneath a breasting means, for example, a reciprocating knife. To insure that the longitudinal median plane of the heel will be presented in proper angular relation to the plane of action of the knife the forward or breast end of the heel is engaged at opposite ends of its breast face during its passage toward the knife by means movable with and by the heel, which means positions the heel with respect to the plane of action of the knife. Since the positioning means engages the forward end of the heel, it is moved with the heel into position beneath the knife and must be removed from such position during operation of the knife. Novel mechanism is provided for releasing the positioning means from engagement with the heel and for moving it out of the way of the knife.

The positioning means may comprise, as shown, fingers having inturned ends normally held toward each other and connected for equal and opposite movement. The heel, as it is fed, separates the fingers by its passage between them and engages, by its breast end, the hooked or inturned ends on the fingers. The fingers are yieldingly held toward each other and against movement with the heel preferably by the same spring so that they move bodily with the heel and the feeding means while maintaining pressure on the breast and sides of the heel to hold the heel against the feeding means during the feeding movement thereof and to position the heel in predetermined relation to the direction of feed and to the plane of action of the knife. The means for removing the fingers from engagement with the heel is shown as independent of the means for moving the fingers out of the path of the knife and is arranged to effect a predetermined separation of the fingers to release their inturned ends from the heel irrespectively of the amount of separation of the fingers as determined by the heel between them. Separation of the fingers to free them from engagement with the breast of the heel allows the spring against which they are moved by the heel to react and draw them back from their position under the knife. To insure against failure of the spring so to act, however, additional means is provided for positively retracting the fingers. As shown, a cam on the knife slide acts on a lever having suitable lost motion connections to a side which carries the fingers to retract the slide and fingers during the initial part of the knife movement.

These and other features of the invention will appear more fully from the following description when read in connection with the accompanying drawings and will be pointed out in the appended claims.

In the drawings,

Fig. 1 is a side elevation of the upper part of a machine embodying the invention;

Fig. 2 is a plan view, parts being removed and broken away to show the construction of the positioning means; and

Fig. 3 is a plan view illustrating the ac-

tion of the feeding and positioning mechanism upon a heel.

The organization of the machine is, in general, similar to the disclosure of the patients above referred to, to which reference may be had for description of parts not herein fully explained.

The machine comprises a column 2 in which a knife slide 4 carrying a knife 6 is mounted for vertical reciprocation by a crank and connecting rod (not shown). A feed table 7 has attached to its inner end by screws 8 a wooden cutting block 9 (Fig. 3). The block 9 is preferably arranged with the end grain of the wood forming the cutting surface of the block. The table 7 has a T-groove 10 formed in its lower face which is engaged by the head 11 of a bolt 12 by which the table is held to a supporting frame 14. At its inner end the frame 14 is supported in a head 16 secured to the upper end of a fixed post 18. The frame 14 has circularly curved tongues 20, 20 which engage corresponding grooves in the head 16, the axis of curvature of the tongues being located in the surface of the cutting block 9 so that the table 7 and the frame 14 may be adjusted about said axis to vary the angular relation of the tread face of the heel on the table to the plane of action of the knife 6. The adjustment is maintained by a bolt 22 passing through a slot 24 and threaded into a downwardly projecting portion of the frame 14. A pointer 26 has its upper end connected to the head 16 for rocking movement about the same center as the frame 14 and has its lower end connected to the bolt 22 so that it moves with the frame 14 and indicates the adjustment thereof relatively to the head 16.

A bracket 28 on the frame 14 (shown partly broken away) supports a magazine comprising a plate 30 to be engaged by the breast end of the heels, the plate being adjustable vertically by a screw 32 against a collar on which the plate is held by a spring 34. The magazine has two side plates 36 which are adjusted toward and from each other by a right and left screw 38 geared to a hand wheel 40 which is supported on the bracket 28. A pair of U-shaped members 42 engage the curved ends of the heels to hold them in the magazine.

A feed slide 46 is provided with tongues 45 which engage grooves 47 formed in the edge faces of the table 7 and is connected by links 48, 48 to the ends of arms 50, 50 of a Y-shaped lever 51 pivoted at 52 to a bracket 54 supported on the post 18. The lever 51 is operated, by mechanism fully described in the before-mentioned patents, to cause the slide 46 to move to the right (Fig. 1) far enough to allow the lowermost heel in the magazine to drop in front of it and then to move in the opposite direction to push the

heel under the knife, so that a portion of its breast end will be removed thereby. If desired, mechanism may be provided, as shown herein and as disclosed in the before-mentioned patents, to give the slide a slight forward movement after the first cut is made to position the heel for a second or finishing cut upon a second operation of the knife. The feed slide 46 has a V-shaped notch (Fig. 3) for engagement with the rounded end of the heel which is being fed, the notch acting laterally to locate the end of the heel engaged by it.

To maintain a downward pressure of the heel while it is being fed, one end of a plate 56 is pivoted at 57 to the plate 32 of the magazine and has its other end loosely connected to a frictionally operated rod 58. On the lower side of the plate 56 is secured a leaf spring 60 which bears on the heel during its feeding movement. When the knife slide starts downwardly the rod 58 is moved by frictional connection therewith to force the plate 56 upon the heel and hold it for the breasting operation.

The rod 58 is straight and extends longitudinally through a bar 62 in which it is threaded for vertical adjustment, such adjustment being maintained by a set nut 63 on its upper end. The bar 62 is frictionally held at 64 in a projecting portion of the knife slide 4 and near its lower end has a recess 65 in its inner face to receive a stationary projection 66 secured to a bracket 68 bolted to the machine frame. The rod 58 passes loosely through a hole in the projection 66 and the projection, by engaging the upper and lower walls of the recess 65, limits the movement imparted to the bar by the knife slide through the friction means 64. The plate 56 therefore, by proper adjustment of the rod 58, is caused to clamp the heel early in the downward movement of the knife and to release it upon the upward movement of the knife.

In order that the heel may be presented with its longitudinal median plane in proper relation (usually normal) to the plane of action of the knife, means engaging the sides and breast corners of the heel during the feeding movement of the heel is provided. A slide 70 (Fig. 2) has on its upper face a T-guide 72 which engages the T-slot 10 in the lower face of the table 7. The slide 70 therefore can move in the direction of movement of the feed slide 46. Pivoted on the slide 70 are two fingers 74, 75 having in-turned ends forming stops which engage opposite ends of the breast face of the heel as it is fed. The fingers 74, 75 have vertical pivot portions 76, 78 mounted to turn in the slide 70. Operatively connected to the pivot 76 of the finger 74 is an arm 80, and secured to the pivot 78 of the finger 75 is an arm 82. The arms 80, 82 extend toward each other

and are geared together so that movement of one finger will move the other equally and oppositely. Connected between the arm 82 and the frame 14 is a tension spring 84 which not only tends to move the fingers toward each other but tends also to move the slide 70, on which the fingers are carried, away from the knife, holding it normally against a stop 85 on the frame 14. The connection of the finger 74 to the arm 80 is as follows: The arm 80 is loose on the pivot 76. Fixed to the pivot 76 is a bevel-toothed segment 88 having an arm 90 in which is threaded a screw 92 that engages a projection 94 on the arm 80. The screw 92 provides for adjustment of the finger 74 relatively to its arm 80 to control the lateral position of the heel between the fingers and causes it to be presented centrally of the knife. The segment 88 also has an arm 96 which limits closing movement of the fingers by engagement with a screw 97 threaded in the slide 70. By adjusting the screw 97 the separation of the fingers when no heel is between them may be controlled.

For opening the fingers to release them from the heel a bevel-toothed pinion 98 meshing with the pinion 88 is fixed to a horizontal rock-shaft 100 journaled in a bracket 102 depending from the slide 70. At the outer end of the rock-shaft 100 is fixed a ratchet segment 104 with which a multiple pawl 106 cooperates. The pawl 106 is shown as in three parts, the teeth being differentially arranged to pick up the ratchet segment 104 in substantially any position of its teeth with respect to the pawl. The three parts of the pawl 106 are each held toward the segment 104 by a separate spring 105, one end of each spring bearing on a part of the pawl and being fixed on its other end to a clamp 110 carried by a sliding block 112. The pawl 106 is pivoted at 114 to a pawl lever 116 which is fulcrumed at 118 on the block 112, a torsion spring 119 being arranged about the pivot 118 of the lever 116 to swing the lever in a clockwise direction to hold the pawl 106 depressed. The block 112 is arranged to slide on a guide 120 formed on the frame 14 and is normally held by a spring 122 against a stop pin 124 on the frame 14. A pin 126 on the slide block 112 limits movement of the pawl 106 toward the segment 104 when the pawl and segment are separated, that is, when the slide 70 is against its stop 85.

The mechanism has now been sufficiently described to enable the operation of this and the remaining mechanism to be readily understood. As shown in Fig. 1, the knife slide 4 is making its upward stroke. The feed slide has been moved to the right to receive a heel from the magazine and has pushed the heel toward the knife 6 under the

leaf spring 60 and between the fingers 74, 75 which were held toward each other by the spring 84 and were separated by the heel against the spring. The lateral position of the breast end of the heel has been determined by pressure of the fingers on the sides of the heel near its breast end. The breast end of the heel has engaged the inturned ends of the fingers and the heel has had its longitudinal median plane A-B (Fig. 3) oriented with respect to the plane of action C-D of the knife, the rear end of the heel having been shifted if necessary in the notch of the feed slide 46. The slide 70 of course was held against the stop 85 by the spring 84 with the segment 104 out of reach of the pawl during the separation of the fingers by introduction of the heel and the pressing of the heel against the inturned ends of the fingers to effect its orientation. Further movement of the heel by the feed slide has caused the heel to move the fingers 74, 75 and the slide 70 on which they are mounted bodily toward the knife, thus bringing the segment 104 into operative relation to the pawl 106, as in the position shown. Since the rotation of the segment by the separation of the fingers took place before the segment and pawl were brought into operative relation, subsequent action, to be described, of the pawl upon the segment will take place irrespectively of the amount the fingers are separated by the heel, that is, irrespectively of the width of the heel. As the upward movement of the slide continues, the feed slide will continue to push the heel toward the knife, and the slide 70 will engage the slide 112 and move it against the tension of the spring 122, the cooperative relation between the pawl 106 and the segment 104 being undisturbed. Finally, the movement of the feed slide will position the breast end of the heel and the fingers 74, 75 beneath the knife. When the knife slide reaches its upper limit, movement of the feed slide will stop, and upon reverse downward movement of the knife slide the friction clamp rod 58 will force the plate 56 against the heel to hold it in position, and before the knife reaches the heel an arm 128 fixed to the knife slide will engage the pawl lever 116 and operate it to lift the pawl 106 and turn the segment 104 in a clockwise direction. This acts through the bevel-toothed segments 98, 88 to open the fingers 74, 75 and release them from the heel. The spring 84 can then react to draw back the slide 70 and remove the fingers 74, 75 mounted thereon from beneath the knife.

Means is provided for withdrawing the fingers positively in case, for any reason, the spring 84 should be ineffective to draw them, thus preventing injury to the knife or breakage to the machine. A lever 130 is

fulcrumed on the bolt 22 with its rounded upper end in the path of a cam 132 secured in the knife slide 6. During descent of the knife slide and before the knife reaches the heel, the cam 132 acts on the lever 130 to swing it clockwise on its fulcrum 22 causing the lower arm of the lever to pull on a link 134 connected to the lower arm of a lever 136 fulcrumed at 138 on the frame 14 and having its upper end connected to the slide 70 by a link 140. This mechanism causes the slide 70 and the fingers 74, 75 to be positively withdrawn in case of failure of the spring 84 to withdraw them. A lost motion connection at 142 between the link 134 and the lever 130 permits the spring 84 to withdraw the fingers and slide without moving the lever 130; the spring therefore can act more quickly to retract the fingers since it does not have to overcome the inertia of the lever 130.

Having thus described my invention, what I claim as new and desire to secure by Letters Patent of the United States is:

25. 1. In a machine of the class described, the combination of means for operating on a shoe blank, means for feeding the blank, and means engaged by the blank after its feeding movement commences and movable therewith to determine the orientation of the blank with respect to the direction of feeding movement.

2. In a machine of the class described, the combination of means for operating on a shoe blank, means engaging one end of the blank to feed it toward the operating means, and means engaged by the opposite end of the blank after its movement commences and movable with the blank to aline the blank with respect to the direction of feed.

3. In a machine of the class described, the combination of means for operating on a shoe blank, means engaging one end of the blank to feed it toward the operating means, and yielding means in the path of the blank being fed to be engaged by the blank after its feeding movement begins and movable by the blank toward the operating means, said yielding means serving to orient the blank with respect to the operating means and to hold it in position until the movement of the operating means begins.

4. In a machine of the class described, the combination of a breasting knife, means for feeding a heel to a position beneath the knife, and means engaged by the heel as it is fed and moved thereby to determine the orientation of the blank with respect to the plane of the knife.

5. In a machine of the class described, the combination of means movable to engage one end of a heel to feed it, means located over the path of the feeding means for operating on the heel, and means engaging the opposite

end of the heel as it is fed and movable with the heel to the end of its movement to aline the heel with respect to the direction of feed and present it in position to be operated upon by the operating means.

6. In a machine for operating on heels, the combination of feeding means movable to engage one end of a heel, means for operating on the heel in the position to which it is fed by the feeding means, and yielding means engaging the opposite end of the heel and movable therewith to the end of its feeding movement to aline the heel with respect to the direction of movement of the feeding means.

7. In a machine for operating on heels, the combination of a feed slide to engage the rounded end of a heel, and fingers between which the heel is presented during its feeding movement and which have inturned ends to engage the breast of the heel at opposite sides to position the heel breast.

8. In a machine for operating on heels, the combination of feeding means operated by power of the machine for engaging the rounded end of a heel, means engaging the heel breast at separated points as the heel is fed, said means being movable with and by the heel to the end of its feeding movement and operating to determine the direction of the longitudinal median plane of the heel with respect to the direction of feeding movement of the heel.

9. In a machine for operating on heels, the combination of a feed slide engaging the rounded end of a heel, fingers having inturned ends to engage the breast of the heel at opposite sides, said fingers being bodily movable with and by the heel, and a retracting spring arranged to move the fingers toward each other and against the tension of which the fingers are moved by the heel.

10. In a machine for operating on heels, the combination of feeding means for engaging the rounded end of a heel, fingers between which the heel is fed and which have inturned ends to engage the breast of the heel, and a spring for closing the fingers and against the tension of which the fingers are movable bodily with the heel.

11. In a machine of the class described, the combination of means for operating on heels, a magazine, means for feeding heels singly from the magazine to the operating means, and means movable with the heel while it is being fed and to the end of its feeding movement, said means acting in opposition to the feeding means to orient the heel with respect to the operating means.

12. In a machine of the class described, the combination of a reciprocating breasting knife, a magazine, a feed slide engaging the rounded end of a heel and acting to present heels one by one from the magazine to the knife, and means engaging the breast of the

- heel and movable with the heel to the end of its feeding movement for orienting the heel with respect to the plane of action of the knife.
- 5 13. In a machine of the class described, the combination of a reciprocating breasting knife, a magazine, a feed slide engaging the rounded end of a heel and acting to present heels one by one from the magazine to the 10 knife, means engaging the breast of the heel and movable with the heel to the end of its feeding movement for orienting the heel with respect to the plane of action of the knife, and means for releasing said breast engaging means from the heel prior to the action of the knife.
- 15 14. A machine of the class described having, in combination, a reciprocating breasting knife, means for feeding heels singly to the 20 knife, fingers located in the path of the heel and arranged to engage the breast end of the heel, said fingers being movable with the heel to its position under the knife, and the means for releasing and retracting the 25 fingers prior to the action of the knife upon the heel.
- 15 15. In a machine of the class described, the combination of means for operating on the 30 breast of a heel, means engaging one end of the heel to feed it toward the operating means, and yielding means in the path of the heel being fed to be engaged by the heel during its feeding movement and movable by the heel to a position beneath the operating 35 means, said yielding means serving to orient the heel breast with respect to the operating means.
- 16 16. In a machine for operating on heels, the combination of feeding means engaging 40 the rounded rear end of a heel, and yielding means engaging the sides and breast end of the heel and moved with and by the heel to align the heel with respect to the direction of movement of the feeding means.
- 45 17. In a machine for operating on heels, the combination of operating means, a feed slide to engage the rounded end of a heel, a second slide movable in the same direction as the feed slide, and fingers carried by the 50 second slide between which the heel is fed, said fingers having inturned ends to engage the breast of the heel at opposite sides to the position the heel breast with respect to the operating means.
- 55 18. In a machine for operating on heels, the combination of a feed slide engaging the rounded end of a heel, fingers engaging the sides of the heel near the breast and having inturned ends to engage the breast 60 of the heel, said fingers being bodily movable with and by the heel, and a retracting spring by which the fingers are closed against the sides of the heel and against the tension of which the fingers are moved by 65 the heel.
19. In a machine of the class described, the combination of means for operating on heels, feeding means for engaging the rounded end of a heel, fingers connected for equal and opposite movement between 70 which the heel is fed and which have inturned ends to engage the breast of the heel, a ratchet connected with the fingers, and a pawl connected with the operating means and cooperating with the ratchet to open the 75 fingers.
20. In a machine of the class described, the combination of means for operating on heels, feeding means for engaging the rounded end of a heel, fingers connected for 80 equal and opposite movement and arranged for bodily movement with the heel, said fingers being separated by introduction of a heel between them and having inturned ends to engage the breast of the heel, a spring for closing the fingers and against the tension of which the fingers are movable bodily with the heel, a ratchet connected to the fingers, and a pawl connected with the operating 85 means and cooperating with the ratchet to open the fingers to permit their retraction by the spring.
21. In a machine of the class described, the combination of means for operating on heels, means for feeding heels singly to the 90 operating means, a slide movable with the heel while it is being fed, and means on the slide to engage the heel breast and acting only after movement of the heel begins to orient the heel with respect to the operating 95 means.
22. In a machine of the class described, the combination of a reciprocating breasting knife, a magazine, a feed slide acting to 100 present heels one by one from the magazine to the knife, a second slide, means on the second slide to engage the breast of the heel and to be moved by the heel during its feeding movement, and means yieldingly opposing movement of said second slide. 105
23. In a machine of the class described, the combination of a reciprocating breasting knife, a magazine, a feed slide acting to present heels one by one from the magazine to the knife, a second slide, spring means for urging the second slide in a direction opposite to the feeding movement of the slide, stops on the second slide against which the heel is pressed by the feed slide to orient 110 the heel with respect to the plane of action of the knife, and means for releasing said stops from the heel prior to the action of the knife to permit said spring means to retract the stops from beneath the knife. 115
24. In a machine of the class described, the combination of a reciprocating breasting knife, means for feeding heels singly to the knife, fingers located in the path of the heel arranged to be separated by introduction of a heel between them and having 120
- 130

inturned ends to engage the breast end of the heel, said fingers being movable with the heel to its position under the knife, and means for separating the fingers to release them from the heel, said means acting irrespectively of the amount the fingers are separated by the heel to separate them a predetermined further amount sufficient to release their inturned ends from the heel breast.

25. In a machine of the class described, the combination of means for operating upon a heel, means engaging one end of the heel to feed it into position to be acted upon by the operating means, and means engaging the opposite end of the heel as it is fed and moved by the heel to aline the longitudinal median plane of the heel with the direction of feed and to perfect the positioning of the heel for the action of the operating means.

26. In a machine of the class described, the combination of means for operating on a heel, means engaging one end of the heel to feed it toward the operating means, and yielding fingers in the path of the heel being fed to be engaged by the other end of the heel during its feeding movement and movable bodily by the heel toward the operating means, said yielding fingers being fixed as to movement relatively to each other longitudinally of the heel and serving to orient the heel with respect to the operating means.

27. In a machine for operating on heels, the combination of feeding means for engaging the rounded end of a heel, a slide, fingers on the slide between which the heel passes in its feeding movement and which have inturned ends to engage the breast of the heel, a spring for closing the fingers and against the tension of which the fingers and slide are bodily movable by the heel, means on the slide for opening the fingers, a pawl, and means for operating on the heel, the finger opening means being arranged to be brought into operative relation to the pawl by movement of the slide by the heel and the pawl to be operated to open the fingers by the means for operating on the heel.

28. In a machine of the class described, the combination of a reciprocating breasting knife, means for presenting heels one by one to the knife, a finger slide, fingers on the finger slide to engage the breast of the heel and movable with and by the heel during its feeding movement for orienting the heel with respect to the plane of action of the knife, means including a ratchet on the finger slide for moving the fingers to release the heel, a pawl slide movable by the finger slide, a pawl on the pawl slide arranged to remain in operative relation to the ratchet when the slides are moved together, and means actuated by the knife for operating said pawl.

29. A machine of the class described having, in combination, a reciprocating breasting knife, means for feeding heels singly to the knife, a slide, resilient means opposing movement of the slide in the direction of feeding movement of the heel, fingers on said slide located in the path of the heel to be engaged by the breast end of the heel, said fingers being movable with the heel to its position under the knife, and means operated during initial operative movement of the knife for releasing the fingers from the heel to permit the resilient means to retract the slide and fingers.

30. In a machine of the class described, the combination of means for operating on heels, feeding means for engaging the rounded end of a heel, fingers connected for equal and opposite movement between which the heel is fed and which have inturned ends to engage the breast of the heel, a ratchet connected with the fingers, and a pawl connected with the operating means and cooperating with the ratchet to open the fingers, said pawl being out of operative engagement with the ratchet prior to engagement of the heel with the inturned ends of the fingers.

31. In a machine of the class described, the combination of means for operating on heels, feeding means for engaging the rounded end of a heel, fingers connected for equal and opposite movement and arranged for bodily movement with the heel, said fingers being separated by introduction of a heel between them and having inturned ends to engage the breast of the heel, a spring for closing the fingers and against the tension of which the fingers are movable bodily with the heel, a ratchet connected to the fingers, and a pawl connected with the operating means, said ratchet being moved into cooperative relation to the pawl upon bodily movement of the fingers and cooperating with the ratchet only after the ratchet and fingers have moved bodily with the heel to open the fingers to permit their retraction by the spring.

32. In a machine of the class described, the combination of a reciprocating breasting knife, a magazine, a feed slide acting to present heels one by one from the magazine to the knife, a second slide, spring means for urging the second slide in a direction opposite to the feeding movement of the slide, stops on the second slide against which the heel is pressed by the feed slide to orient the heel with respect to the plane of action of the knife, means for releasing said stops from the heel prior to the action of the knife, and means for positively withdrawing the stops from beneath the knife.

33. In a machine of the class described, the combination of a reciprocating breasting knife, means for feeding heels singly to

the knife, fingers located in the path of the heel arranged to be separated by introduction of a heel between them and having inturned ends to engage the breast end of the heel, said fingers being movable with the heel to its position under the knife, means for separating the fingers to release them from the heel, and means for positively withdrawing the fingers from beneath the knife.

34. In a machine of the class described, the combination of means for operating on a heel, means engaging the rear end of the heel to feed it toward the operating means, yielding fingers in the path of the heel being fed to be engaged by the front end of the heel during its feeding movement and movable bodily by the heel toward the operating means, said yielding fingers being fixed as to movement relatively to each other longitudinally of the heel and serving to orient the heel with respect to the operating means, and means for removing the fingers out of the way of the operating means.

35. In a machine for operating on heels, the combination of feeding means for engaging the rounded end of a heel, fingers between which the heel passes in its feeding movement and which have inturned ends to engage the breast of the heel, and means for opening the fingers to release their in-

turned ends from the heel irrespectively of the distance the fingers are separated by the heel.

36. In a machine of the class described, the combination of a reciprocating breasting knife, means for presenting heels one by one to the knife, a finger slide, fingers on the finger slide to engage the heel and movable by the heel during its feeding movement, means including a ratchet on the finger slide for releasing the fingers from the heel, a pawl slide movable by the finger slide, a pawl on the pawl slide arranged to remain in operative relation to the ratchet when the slides are moved together, and means actuated by the knife for operating said pawl and for retracting the finger slide.

37. A machine of the class described having, in combination, a reciprocating breasting knife, means for feeding heels singly to the knife, a slide, stops on said slide located in the path of the heel to be engaged by its breast end, said stops being movable with the heel to its position under the knife, and means operated during initial operative movement of the knife for releasing the stops from the heel and retracting the slide and stops.

In testimony whereof I have signed my name to this specification.

IRA C. BUCKMINSTER.
